INTERLOCKING CONTROL SYSTEM FOR APPARATUS VALVES OF WATER GAS SETS

Filed May 3, 1923

2 Sheets-Sheet 2

UNITED STATES PATENT OFFICE.

FRED B. HAYES, OF FORT WAYNE, INDIANA, ASSIGNOR TO THE WESTERN GAS CONSTRUCTION COMPANY, OF FORT WAYNE, INDIANA, A CORPORATION OF INDIANA.

INTERLOCKING CONTROL SYSTEM FOR APPARATUS VALVES OF WATER-GAS SETS.

Application filed May 3, 1923. Serial No. 636,419.

To all whom it may concern:

Be it known that I, FRED B. HAYES, a citizen of the United States, residing at Fort Wayne, in the county of Allen and 5 State of Indiana, have invented certain new and useful Improvements in Interlocking Control Systems for Apparatus Valves of Water-Gas Sets, of which the following is a specification, reference being had to the 10 accompanying drawings, and to the reference characters marked thereon, which form a part of this specification.

This invention relates to means for automatically controlling water gas apparatus, 15 and more particularly for controlling the action of fluid pressure cylinders for operating the various apparatus valves in such gas apparatus.

In the manufacture of water gas, as it is 20 commercially practiced at the present time, the operations are such as to require the manipulation of a number of valves in certain sequence and at certain intervals, which requires considerable skill and constant attention on the part of the operators in order 25 to avoid errors which may cause explosions, and in order to produce a gas of uniform quality, and the maximum results in quantity and quality of gas of which the apparatus is capable.

Briefly stated, the gas making apparatus comprises a generator, carburetter, and superheater provided with a stack. There are sources of air supply to the generator 35 and to the carburetter; steam supply to the generator, and oil to the carburetter; all valve controlled; and, of course, the necessary piping.

The operation of such an apparatus or 40 "water gas set," as it is called in the trade, is divided into two periods known as the "blast" and the "run." The "blast" serves to raise the temperature of the fuel bed in the generator and the checker bricks of the carburetter and superheater to produce an incandescent heating surface, and the "run" 45 is the gas-making period.

Presuming that the generator is charged with fuel, the "blast" is started in the following manner: The stack valve being open; the generator blast valve will be opened to admit air under pressure below the fire. The gases produced by the combustion pass through a reversing valve, generally known

as a "hot valve," to the carburetter, where 55 they burn upon meeting a current of air which has been admitted into the carburetter by the opening of the carburetter blast valve, and from thence to the superheater and to the stack. These valves, namely the 60 generator air blast, carburetter air blast, hot valve, and the stack valve, will remain open for a period of time, generally about three minutes, after which the carburetter air blast valve will first be closed, and then the 65 generator air blast valve will be closed. This blast period having been completed, the fuel in the generator and the checker brick of the carburetter and superheater will be in an incandescent condition. 70

The "run" or actual gas-making period, of approximately four minutes, is started by first opening the generator steam valve, to admit steam under the incandescent fuel. Immediately after the opening of the steam 75 valve, the stack valve will be closed, and then the carburetter oil valve opened. After the predetermined interval of time, it is desirable to reverse the run of the steam by passing it down through the bed of incandescent fuel in the generator instead of upwardly therethrough. This is accomplished by reversing the "hot valve" which 80 automatically governs the admission of steam into the generator. At the end of 85 this down-run, the carburetter oil valve is closed and the hot valve again reversed to admit steam for a very brief up-run, after which the generator steam valve is closed. The stack valve is opened immediately after 90 the steam valve is closed.

From the foregoing, it will be manifest that in a complete cycle of operations, a considerable number of valves must be opened and closed in every six to eight minutes. 95 Furthermore, the operation of the various valves must occur in the proper order and at proper time intervals, as the failure of any of the valves to properly operate may produce dangerous conditions in or about 100 the apparatus.

To insure the proper operation of the various parts of the apparatus, it has been proposed to mechanically operate the various valves of the water gas set by means of a fluid pressure cylinder connected with each main valve, and also to regulate these cylinders, or the flow of the fluid thereto, 105

by automatic devices called a "mechanical man" or "timing machine." It has also been proposed to make the timers not only automatic but interlocking, so that the timer, as a unit, will cease to operate if one of its own parts fails to properly function. A serious difficulty, however, is experienced when one of the apparatus valves or its operating cylinder breaks or fails to function properly or at the right time. In such event, the timing machine, being intact, will continue to function and force the fluid under pressure to the other valve-operating cylinders which will operate their respective apparatus valves, thus producing improper conditions in the water gas set, which generally result in damage thereto and loss of gas and, not infrequently, in explosions.

The invention consists of an interlocking control system for apparatus valves of a water gas set comprising a plurality of what I shall hereinafter call "control valves", each valve being located in a conduit which supplies the motive power or operating fluid for a particular motor or apparatus valve-actuating device, and means connecting said control valves to the various apparatus valve motors whereby the action of an apparatus valve will govern the action of the control valve.

It is the main object of the present invention to obviate all of the above mentioned objections and to eliminate possibility of improper action of the apparatus valves due to any cause. My object is to produce an interlocking control system in the conduits carrying fluid under pressure to the valve-operating cylinders of a water gas set, and to automatically control or interlock the operating cylinders for the apparatus valves, whether the operating fluid for said cylinders is controlled manually or by timer machines automatically operated.

Another object of my invention is to connect a system of signals with the control system, whereby notice of anything having gone wrong will be conveyed to the operator.

These and other objects and advantages of my invention will be manifest as I proceed with my specification, my invention consisting in the control system and in the devices and combination of devices herein illustrated, described, and more particularly pointed out in the claims hereto appended.

In the accompanying drawings, I have illustrated my invention as applied to a conventional water gas set, but it will be apparent that it is applicable to other forms of apparatus and that the various details of mechanical construction may be modified by those skilled in this art to suit the needs of any particular installation.

In said drawings:

Fig. 1 is a diagrammatic elevation, partly

in section, of a conventional water gas apparatus which has its main or apparatus valves actuated by a series of fluid pressure cylinders, with my interlocking control system applied thereto.

Fig. 2 is a diagrammatic elevation, partly in section of a portion of the said apparatus, but on a somewhat larger scale.

That form of apparatus to which my invention is applied as shown in Fig. 1 will now be described for the purpose of identifying the various parts, and subsequently I will point out the method of operation of the various features more in detail by reference to Fig. 2.

The water gas apparatus or "set" illustrated in Fig. 1 comprises a generator A, carburetter B, superheater C, a source of air supply E (as from a blower, not shown), a source of oil supply F, a source of steam supply G, apparatus valves such as the generator blast valve H, carburetter blast valve I, stack valve J, reversing or "hot" valve K, stem valve L and oil valve M; also a water seal or wash box N, a timer machine O, and numerous pipe lines or conduits hereinafter referred to.

The main or apparatus valves H, I, J, K, L and M, are operated from the cylinders 1, 2, 3, 4, 5 and 6, respectively, in a familiar manner, and any suitable fluid under pressure, as for example, water, gas, oil, or air, is sent from the timer machine O to the several cylinders 1, 2, 3, 4, 5 and 6, and returned to the timer by a circulatory system of piping. The timer O is supplied with an inlet or supply pipe P and an exit or outlet pipe Q.

An exit *i* in the dome of the superheater C leads by a tee-connection both to the stack and to the water seal N. The air blast leads from the pipe E through the valve H to the generator inlet port *c*; and to the carburetter, through the valve I to the pipes *g* and *d* to inlet port *f*.

In the steam supply line G and between the steam valve L and the generator steam lines 7 and 8, is a two-way steam valve D, which is operatively connected with the reversing valve K, whereby steam is supplied through the line 7 to the lower port *a* of the generator for the up-run and through the line 8 to the upper port *b* for the down-run. An oil supply pipe F, when the valve M is opened, furnishes a spray of oil to the carburetter B, through a suitable nozzle.

R is a whistle in the air line *r* connected to the air conduit between the generator blast valve H and the generator A. S is a steam whistle connected by the line *s* to the steam supply pipe between valves L and D.

The cylinder 1 for operating the generator blast valve H is actuated by fluid under pressure from the timer O through the conduits or lines 9 and 10. The cylinder 2 which actuates the carburetter air blast valve

- I has a connection with the timer O through the conduit or line 11 and 12. The cylinder 3 which actuates the stack valve J connects with the timer O by the conduits 13 and 14. 5 The cylinder 4 which actuates the hot valve K connects with the timer O by the conduits 15 and 16. The cylinder 5 which operates the steam valve L connects with the timer O by conduits or lines 17 and 18. The cylinder 6 which actuates the oil valve M connects with timer O by the conduits or lines 19 and 20.
- When the steam is on the down-run, the gas produced passes out of the exit c to a branch pipe 21, through the hot valve K and through the pipe 22 and conduit d to the carburettor B.
- Further details need not be stated as the gas set just described is conventional and 20 well known. To such an apparatus I apply my invention, as more fully shown in Fig. 2.
- I will now proceed to describe my interlocking control system, which, it will be seen by reference to Fig. 2, includes a series of 25 small interlocking or control valves designated by the numerals 25 to 38, inclusive, located in the various conduits 9 to 20 inclusive, which conduits supply the operating fluid under pressure to the cylinders which 30 actuate the apparatus valves H, I, J, K, L and M; the control valves being so connected together and with the various parts of the gas set, as hereinafter more fully explained, as to open or close off, as the case may be, the 35 fluid supply in said conduits to the cylinder which actuates the valve which is designed to operate in the next succeeding cycle of operations, and to influence certain other parts of the system, by locking the valve-operating cylinders against operation, so that no 40 valve-operating cylinder will operate or start to operate until (and only when) the valve operated by the cylinder next proceeding in the cycle of operations has completed 45 its work and has fully functioned. This interlocking or control of the movement of of any one of the said apparatus valves occurs equally, whether the flow of liquid under pressure through said control valves 50 is toward or from the valves; that is, whether the control fluid is operating in a direction to cause the opening of a given apparatus valve or in the opposite direction to cause the closing of said valve. It will also be 55 understood that the fluid to actuate the several cylinders may, so as my invention is concerned, be supplied from any suitable source other than from the timer machine O hereinbefore referred to.
- 60 It will be seen that the pipe line or conduit 9 is provided with valves 25 and 26; the pipe line 10, with a valve 27. The line or conduit 11 connected with the carburettor blast valve operating cylinder 2, is 65 provided with a valve 28. The conduit or line 13 connected with the stack valve operating cylinder 3 is provided with valves 29, 30 and 31, while its companion line 14 is provided with a valve 32. The line 16 from the hot valve operating cylinder 4 is provided with a valve 33. The line or conduit 19 from the oil valve operating cylinder 6 is provided with valves 34 and 35.
- The steam whistle line s is provided with valves 36 and 37 and the air whistle line r 70 has a valve 38. The valves 26, 27, 29, 30, 31 and 32 are provided with springs 39, 40, 41, 42, 43, and 44, respectively, to insure prompt action for the purpose hereinafter explained.
- The cylinder 1 has a piston 45, piston rod 46 connected by a suitable coupling 47 with the valve stem or lever 48 of the blast valve H. Secured to the valve actuating stem or lever 48 are two arms 49 and 50; the outer end of the arm 49 straddles and has sliding connection with a rod 51 which connects the valves 28 and 38. Fixed upon said rod 51 are two spaced apart collars or shoulders 52, 53, the end of the arm 49 being between said collars. The valve 29 has a stem 54 80 similarly provided with fixed collars 55 and 56 and the end of the arm 50 has sliding engagement with the stem 54 between said collars 55 and 56.
- Similarly, the valves 26 and 30 are provided with stems 57 and 58, respectively, and these stems have fixed, spaced apart collars 59, 60, and 61, 62, respectively. The cylinder 2 has a piston 63, piston rod 64, and coupler connection 65 to the arm or stem of 85 the carburettor blast valve I. Upon the latter are rigidly secured the two arms 66 and 67, which have sliding engagement at their ends with the stems 57 and 58, respectively.
- The cylinder 3 has a piston 68, piston rod 69, and coupling 70, by which it is connected with the lever or stem of the stack valve J, and the said valve stem or lever is provided with two fixed arms 71, and 72, the outer ends of which have sliding connection with the stems or rods 73 and 74, respectively. The rod 73 connects the valves 25, and 36, and is provided with two spaced apart collars 75 and 76, one on each side of 90 the arm 71. Similarly the stem 74 connects valves 33 and 34, and has collars 77 and 78 for contact with the arm 72.
- The cylinder 4 has a piston 79, piston rod 80 and coupler connections 81 with the arm or lever 82 of the hot valve K, and the said lever is provided with rigid arms 83 and 84. The arm 83 has sliding connections between the collars 85 and 86, on the stem 87 of the valve 27, while the arm 84 has sliding connection between collars 88 and 89, on the stem 90 of the valve 32.
- The cylinder 5 has a piston 91, stem 92, and a coupler connection 93 with the lever or stem of the steam valve L on which valve 130

lever or stem is an arm 94. The valves 35 and 37 are connected by a stem or rod 95 carrying spaced apart collars 96 and 97, between which the end of the arm 94 projects and 5 has sliding engagement with the rod 95.

The cylinder 6 has a piston 98, piston rod 99 and coupler connection 100 with the stem of the oil valve M. To the said stem is rigidly secured the arm 101, the end of which 10 has sliding engagement with the stem 102 of the valve 31, which stem 102 carries the spaced apart collars 103 and 104.

The operation of my interlocking control system which includes the control valves 25 15 to 38, inclusive, and their operative connections with the cylinders or motors which actuate the apparatus valves will be comprehended as I now proceed to describe the operation of the water gas set and the control 20 system in the various operations, commencing with the "blast" period.

Assuming the stack valve J to be open, and the blower turned on, the first valve to be operated is the generator blast valve H. 25 The diagram, Fig. 2, shows the generator blast cylinder 1 with its piston 45 down, indicating that the generator blast valve H is in the closed position. To open the valve H, fluid under pressure is sent to the cylinder 1, through the conduit or line 9, to raise the piston and its connected generator blast valve. Immediately the generator blast valve H commences to open by means of the upward travel of the piston 45 in cylinder 30 35 1, and of the arm 50 travelling therewith, pressure is removed from the spring 41, whereupon the control valve 29 located in the stack valve conduit 13 is actuated, resulting in stopping circulation of fluid in conduit 13 and thus holding the stack valve J open while the generator blast valve H is open. In other words, the very beginning 40 45 of the opening operation of the generator blast valve H results in locking the stack valve J in open position.

When the generator blast valve H has almost reached its open position, the piston 45 being almost at the top of the cylinder, the arm 49 on the valve stem 48 will come in 50 contact with the collar 52 on the stem 51 of the control valve 28 located in conduit 11, thereby opening this control valve 28 and permitting fluid to flow through the conduit 11 to the carburetter blast cylinder 2. The 55 position of the shoulder 52 on the stem 51 is such, with reference to the length of throw of the valve stem 48, that the arm 49 will contact with said shoulder 52 at the proper time, whereby the desired short opening 60 movement of the control valve 28 will take place. It will be manifest that the cylinder 2 and the valve I cannot operate until the conduit 11 is opened, and this will not occur until the generator blast valve H has fully 65 and properly functioned.

The diagram, Fig. 2, shows the piston 63 of the carburetter blast valve cylinder 2 in the down position, indicating the carburetter blast valve I is closed, and the conduit 11 leading to said cylinder also closed by the 70 valve 28. As just explained, the complete operation of the generator blast valve H has withdrawn any obstruction in this conduit 11 by opening the valve 28, leaving the valve I in position to be opened as soon as it is 75 time to operate said valve I in the cycle of operations.

Immediately the carburetter blast valve begins to open by means of the upward travel of the piston 63 in the cylinder 2, 80 pressure of the arm 67 is removed from the spring 42 which actuates the control valve 30 located in the stack valve conduit 13, thereby quickly closing said control valve 30, and making circulation in the stack valve 85 conduit 13 impossible. The stack valve J will therefore necessarily remain in the open position while the carburetter blast valve I is open, even if anything should go wrong with the generator blast valve mechanism. 90

The opening operation of the carburetter blast valve I, through its valve stem and the arm 66, also releases pressure on the spring 39 which actuates the control valve 26 located in the conduit 9, thus locking the generator blast valve H in open position while the carburetter blast valve is open. 95

From the foregoing it will be clearly understood that the stack valve J is locked in the open position by the opening operations 100 of both the valves H and I, as well as by either one of them; that the carburetter blast valve I is not permitted to open until the generator blast valve H has fully opened; and that the generator blast valve 105 H is locked in the open position while the carburetter blast valve is open.

The valves just referred to will remain in the open position for the time required for the "blast" period, after which the carburetter blast valve I will be closed by means of fluid directed through the conduit 12 above the piston 63 in the cylinder 2. The closing of the valve I and consequent reverse travel of the cylinder piston 63 will cause the arm 110 66 to contact with the shoulder 60 on the stem of the control valve 26 in conduit 9, thereby opening said control valve 26 and permitting circulation of fluid in the generator blast conduit 9 and permitting the generator blast valve H to be closed, following the complete closing of the carburetter blast valve I. At this point in the cycle of operations, the stack valve J is still open, and the generator blast and carburetter blast valves 115 H and I are closed. 120

To commence the "run" period, fluid is now directed through the conduit 17 to operate the cylinder 5 which actuates the generator steam valve L. As shown in the 130

diagram, Fig. 2, the generator steam valve L is closed, the piston 91 being at the bottom of the cylinder 5. The conduits 17 and 18 are unobstructed and the valve L free to operate. The opening movement of the steam valve L, by means of its valve stem and connected arm 94, causes contact with the shoulder 96 on the stem 95 of the control valve 35 in the conduit 19 leading to the carburetter oil valve cylinder 6. This contact of the arm 94 with said shoulder 96 is timed to take place when the steam valve L is almost completely open, and this is accomplished by properly positioning the shoulders 96 and 97 on the stem 95 to provide for the necessary sliding or lost motion of the arm 94 before it functions to operate the valves 35 and 37. Therefore, if the generator steam valve L does not fully operate, it follows that the carburetter oil valve M will not be permitted to open, because fluid in the oil valve cylinder conduit 19 cannot circulate when the control valve 35 has not been operated by the movement of the valve stem arm 94 to open said conduit 19. The piston 98 in the oil valve cylinder 6 will, therefore, be held against movement and the oil valve M locked in the closed position. When the generator steam valve L fully functions for the opening operation, the conduit 19 will be unobstructed (except by the valve 34 controlled from the stack valve, and hereinafter referred to).

Immediately following the opening of the generator steam valve L, at the beginning of the "run", the stack valve J must be closed. The conduits 13 and 14 to the stack valve cylinder 3 will be unobstructed (following the proper and complete closure of the generator blast valve H and carburetter blast valve I) so that the stack valve J may be closed at the desired time by directing fluid through the conduit 14 above the piston 68 to lower the latter in the cylinder 3.

This closing of the stack valve causes the arms 71 and 72, connected to said stack valve stem, to contact with the shoulders 76 and 78 respectively, on the stems of the two control valves 25 and 34. In both instances, the contact takes place at the end of the thrust of the stack valve cylinder piston 68 or when the stack valve J is almost completely closed. The arm 71 contacts with the shoulder 76 on the stem of the control valve 25 in the generator blast conduit 9, and at the completion of the closing movement of the stack valve, the control valve 25 is closed and circulation stopped in the conduit 9, so that the generator blast valve H is locked and could under no circumstances be opened while the stack valve J is closed. The arm 72, in accompanying the valve stem on its downward movement to close the stack valve J, contacts with the shoulder 78 on the stem of the control valve 34 and opens the latter and the conduit 19, thus permitting circulation of fluid therein. Connected to the stem of the control valve 34 is the control valve 33 located in the hot valve conduit 16. The same operation which opens the valve 34 in conduit 19, therefore, opens the valve 33, and permits fluid to flow through the conduits 15 and 16 to the hot valve operating cylinder 4.

It is to be understood from the foregoing that at a certain time in the "run" or gas making period the mechanical conditions in the set are such that the operating fluid may be directed to the generator steam cylinder 5 to open the valve L and admit steam to the generator. At that moment the stack valve J is still open, and the hot valve K is locked in the up-run position by means of the valve 33 controlled by the arm 72 fixed to the stack valve stem. It will also be understood that the complete opening of the steam valve L has resulted in opening the control valve 35 in the carburetter oil valve conduit 19, but that said oil valve M is still locked against operation because of the closed valve 34 in conduit 19 controlled by the stack valve J.

Therefore, immediately after the steam valve L has been fully opened, fluid is directed through conduit 14 to close the stack valve J. The end of the stroke of the valve J in closing results in opening the control valve 34, so that immediately after the closing of the stack valve J fluid may be directed through conduits 19, and 20, to said carburetter oil valve cylinder 6 to open the oil valve M. Water-gas formed by the steam passing through the generator in the "up-run" and through the hot valve K to the carburetter may thus be enriched with oil sprayed upon the gases. This same movement of the stack valve J, in closing, has also closed the control valve 25 in the conduit 9, so that the generator blast valve H is locked against operation while the stack valve is closed. The closing of the stack has further resulted in opening the control valve 33 in the hot valve conduit 16, so that said conduit is now unobstructed. When it is desired to reverse the flow of steam for the down-run in the generator A, fluid will be directed in conduit 16 to the hot valve cylinder 4 to operate the hot valve K. After the desired "down-run" the fluid in conduits 15, and 16, may be directed to reverse the hot valve for the brief "up-run" period.

It will be seen from Fig. 2, that when the carburetter oil valve M has been permitted to open (following the removal of conduit obstructions by the opening of the generator steam valve and the closing of the stack valve, as above explained), the opening movement of the carburetter oil valve stem carrying the arm 101 releases pressure on

the spring 43 and results in closing the control valve 31 in the stack valve conduit 13, so that the stack valve J (having been previously closed) is locked in closed position 5 while the carburetter oil valve is open.

- The operation of the hot valve in reversing to its "down-run" position, has two effects. Immediately the piston 79 in the hot valve cylinder 4 begins its downward stroke, 10 the arms 83 and 84 travel downwardly and release pressure on the springs 40 and 44 in the control valves 27 and 32, respectively, thereby closing the valve 32 in the stack valve conduit 14 and the valve 27 in the generator blast conduit 10, locking the stack valve J against opening while the hot valve K is in the down-run position, and locking the generator blast valve H against opening 15 during the same period of time.
- At the end of the "run" period, and practically simultaneously with the reversing of the hot valve K from the down-run to the up-run positions, fluid is directed to the carburetter oil valve cylinder 6 to close the valve M. The closing of the oil valve M 20 operates to open the control valve 31 in the conduit 13, leaving that conduit unobstructed and the stack valve J free to be opened.

- Next in the operation, fluid is directed to 25 the steam valve cylinder 5 to close the valve L, and then fluid is directed through conduit 13 to the stack valve cylinder 3, to open the stack valve J. This opening of the stack valve J at the end of the stroke of the valve stem, opens or unlocks the control valve 25 30 in the generator blast conduit 9 and leaves that conduit unobstructed and the generator blast valve H free to operate. The opening of the stack valve J also closes control valve 40 34 in the conduit 19, thereby locking the oil valve M against opening, and closes control valve 33 in conduit 16, thereby locking the hot valve K in its up-run position, which is the position it will hold during the following 45 "blast" period.

- So now, at the end of the "run," we have the stack valve open, the generator steam valve closed, the carburetter oil valve closed and locked against opening until the stack 50 valve and generator steam valves have again been operated, and the hot valve in the up-run position and locked against movement while the stack valve is open. Also, we have the generator blast valve closed but ready to be opened when fluid is directed to its operating cylinder, and the carburetter blast valve closed, but ready to operate immediately after the generator blast valve has completed its opening operation and unlocked 55 the control valve 28 now closed in the conduit 11.

In this position, the set is ready for the next "blast" period.

Some of the control valves, those designated 60 26, 27, 29, 30, 31 and 32, are designed

to be operated quickly, under the influence of their springs, when the arms 66, 83, 50, 67, 101 and 84, respectively, are operated. However, auxiliary means are provided whereby said valves will be operated in the 70 event anything should go wrong with said springs. For example, the arm 66 in its upward travel will contact with the shoulder 59 to close the valve 26; arm 67 will contact with shoulder 61 to close valve 30; arm 75 50 with shoulder 55 to close valve 29; arm 83 with shoulder 86 to close valve 27; arm 84 with shoulder 88 to close valve 32, and arm 101 with shoulder 104 to close valve 31.

The means for signalling the operator by 80 the steam whistle S and the air whistle R will now be described. Just at the beginning of the "run" period, after the steam valve L has fully operated, the control valve 37 in the steam whistle conduit s will be 85 opened, permitting steam to pass to the whistle which blows momentarily, indicating that the apparatus is in order and shifting from the blast period to the "run" 90 period.

As heretofore stated, the stack valve J must be closed immediately after the generator steam valve L is opened. The stack valve, by means of the arm 71, actuates a control valve 36 in the steam whistle conduit s, closing said valve 36 when the stack valve has almost completely closed; the closing of the control valve 36 stopping the sound of the whistle.

Therefore, the momentary blowing of the 100 steam whistle indicates the proper operation of the valves during the blast period, and the stopping of the sound indicates the closing of the stack valve, preparatory to the "run" period.

At the end of the "run", the control valve 38 in the air whistle line r is open. When, at the beginning of the "blast" the generator blast valve H is opened, air will pass through the air line r to the whistle R which 110 will sound for a moment, for when the valve H is fully opened the arm 49 will have contacted with the shoulder 52, thus closing the air line control valve 38. If, however, anything had gone wrong during the gas making run period, the generator blast valve would not fully open, the arm 49 would not close the valve 38 and consequently air would flow through conduit r and the whistle R continue to blow until the operator 120 gave the necessary attention to the apparatus.

The control valves 25, 26, 27, 28, 29, 30, 31, 32, 33, 34, 35, 36, 37 and 38 are shown herein as small cylinders containing reciprocating pistons to open and close the inlet and outlet ports; and this is a convenient mechanical form of apparatus in the several fluid conduits to control the flow. In practice, the travel of the piston is from $\frac{1}{4}$ to 130

5 $\frac{3}{8}$ of an inch and these little piston valves answer all requirements. However, it is to be understood that other forms of control valve are equally applicable, the only requirement being that the valve located in the designated conduit is adapted to be mechanically connected to the parts which operate and control it, so as to completely open or close the conduit to permit or shut 10 off the flow of fluid therethrough.

Various other changes may be made by the skilled mechanic according to the necessities of each installation as previously stated.

15 It will be noted that the mechanism for actuating the control valves is so connected with the apparatus valves, that if anything should go wrong, as for example if the connecting rod between a cylinder and its apparatus valve stem should break, there would be no interference with the actuation of the control valves by the operation of the apparatus valve. In other words, when 20 the apparatus valves function, the control valves will be also actuated to open or close, as the case may be, and either permit or prevent circulation in the fluid conduits to the apparatus valve cylinders.

It is to be noted that the control valves 25 29, 30, 31 and 32 in the stack valve cylinder conduits 13 and 14, and the control valves 26 and 27 in the generator blast valve cylinder conduits 9 and 10 are preferably spring actuated so that the moment pressure is released from said springs by the beginning of 35 movement of the apparatus valves associated with said control valves, the latter will instantly be actuated.

Whenever a control valve is closed so as 40 to stop circulation in a particular valve-operating cylinder conduit and to hold the apparatus valve in inoperative position, such closing of the control valve occurs, under influence of its spring, immediately 45 upon the beginning of movement of the apparatus valve with which said control valve is operatively connected.

Whenever a control valve is opened so as 50 to permit circulation in a particular valve-operating cylinder conduit and leave the apparatus valve free to operate, such opening of the control valve occurs only when the apparatus valve with which it is connected has almost fully operated.

55 It will therefore be understood that the interlocking of the apparatus valves to render them inoperative occurs when a particular apparatus valve begins to function, while the unlocking of the system to render 60 the apparatus valves operative occurs when, and only when, a particular apparatus valve or valves have completely operated.

From the foregoing description it will be 65 seen that I have provided means whereby the operation of the apparatus valves of a water

gas set are positively governed, embodying a system of interlocked parts whereby the operation of a given apparatus valve in one cycle of the operation of the set will lock one or more apparatus valves in an inoperative position, and will permit of the operation of certain other apparatus valves only upon the completion of the operation and full and proper functioning of the said given apparatus valve.

70 75

I claim as my invention:

1. In a water gas apparatus provided with fluid actuated cylinders for operating the apparatus valves and with fluid conduits for said cylinders, a valve located in the fluid conduit to control a cylinder, which valve in turn is controlled by an apparatus valve.

2. In a water gas apparatus provided with actuating cylinders for operating the apparatus valves and with fluid conduits for said cylinders, a plurality of interlocking control valves located in the fluid conduits and means associated with the apparatus valves of the set and with said control valves to lock one or more of said apparatus valves in an inoperative position upon the operation of certain other apparatus valves.

3. In a water gas apparatus provided with fluid actuated cylinders for operating the apparatus valves and with fluid conduits for said cylinders, a plurality of interlocking control valves located in the fluid conduits and operative connections between said control valves and the cylinders for operating the apparatus valves of the set whereby certain of said apparatus valves will operate only upon the proper and complete functioning of another apparatus valve.

4. In a water gas apparatus provided with fluid actuated cylinders for operating the apparatus valves and having fluid conduits for said cylinders, a plurality of interlocking control valves located in the fluid conduits and operative connections between the control valves and said cylinders, whereby certain of said control valves will be actuated to close the fluid conduits at the beginning of the movement of the apparatus valve, while other control valves will be actuated to open the fluid conduits only at the extreme end of the movement of the apparatus valves.

5. In a water gas apparatus provided with fluid actuated cylinders for operating the apparatus valves, and fluid conduits for said cylinders, a control valve located in one of the fluid conduits, operative connections between the control valve and the cylinders for actuating the apparatus valves, said connections including means associated with the control valve to close the latter upon the beginning of the movement of an apparatus

valve, and means associated with the control valve for opening the latter at the extreme end of the movement of an apparatus valve.

6. In a water gas apparatus provided with fluid actuated cylinders for operating the apparatus valves, and fluid conduits for said cylinders, a system of interlocking control valves located in the fluid conduits, and operative connections between said cylinders and said control valves.

7. In a water gas apparatus provided with fluid actuated cylinders for operating the apparatus valves and having fluid conduits for said cylinders, a system of control valves located in the fluid conduits, means associated with the apparatus valves for controlling the movement of said control valves, the latter being so interlocked as to prevent the operation of a given apparatus valve until 20 the apparatus valve next preceding it in the cycle of operations of the water gas apparatus shall have completely and fully functioned.

8. In a water gas apparatus wherein the apparatus valves are operated by fluid actuated cylinders and having fluid conduits for said cylinders, a plurality of control valves located in the fluid conduits, and operative means whereby the control valve in the conduit leading to the carburetter blast valve-operating cylinder will be actuated by the operation of the generator blast valve.

9. In a water gas apparatus wherein the apparatus valves are operated by fluid actuated cylinders and having fluid conduits for said cylinders, a plurality of interlocking control valves located in the fluid conduits, and operative means whereby the control valve in the conduit leading to the carburetter blast valve-operating cylinder will be opened by the opening of the generator blast valve.

10. In a water gas apparatus wherein the apparatus valves are operated by fluid actuated cylinders and having fluid conduits for said cylinders, a plurality of interlocking control valves located in the fluid conduits, and operative means whereby the control valve in the conduit leading to the stack valve-operating cylinder will be actuated by the operation of the generator blast valve.

11. In a water gas apparatus wherein the apparatus valves are operated by fluid actuated cylinders and having fluid conduits for said cylinders, a plurality of interlocking control valves located in the fluid conduits, and operative means whereby the control valve in the conduit leading to the stack valve-operating cylinder will be closed by the opening of the generator blast valve.

12. In a water gas apparatus wherein the apparatus valves are operated by fluid actuated cylinders and having fluid conduits for said cylinders, a plurality of interlocking control valves located in the fluid conduits,

an air whistle alarm, and operative means whereby the control valve in the conduit leading to the air whistle will be actuated by the operation of the generator blast valve.

13. In a water gas apparatus wherein the apparatus valves are operated by fluid actuated cylinders and having fluid conduits for said cylinders, a plurality of control valves located in the fluid conduits, an air whistle alarm, and operative means whereby the control valve in the conduit leading to the air whistle will be closed by the opening of the generator blast valve.

14. In a water gas apparatus wherein the apparatus valves are operated by fluid actuated cylinders and having fluid conduits for said cylinders, a plurality of control valves located in the fluid conduits, and operative means whereby the control valve in the conduit leading to the stack valve-operating cylinder will be actuated by the operation of the carburetter blast valve.

15. In a water gas apparatus wherein the apparatus valves are operated by fluid actuated cylinders and having fluid conduits for said cylinders, a plurality of control valves located in the fluid conduits, and operative means whereby the control valve in the conduit leading to the stack valve-operating cylinder will be closed by the opening of the carburetter blast valve.

16. In a water gas apparatus wherein the apparatus valves are operated by fluid actuated cylinders and having fluid conduits for said cylinders, a plurality of control valves located in the fluid conduits, and operative means whereby the control valve in the conduit leading to the generator blast valve-operating cylinder will be actuated by the operation of the carburetter blast valve.

17. In a water gas apparatus wherein the apparatus valves are operated by fluid actuated cylinders and having fluid conduits for said cylinders, a plurality of control valves located in the fluid conduits, and operative means whereby the control valve in the conduit leading to the generator blast valve-operating cylinder will be opened by the closing of the carburetter blast valve.

18. In a water gas apparatus wherein the apparatus valves are operated by fluid actuated cylinders and having fluid conduits for said cylinders, a plurality of control valves located in the fluid conduits, and operative means whereby the control valve in the conduit leading to the oil valve-operating cylinder will be actuated by the operation of the generator steam valve.

19. In a water gas apparatus wherein the apparatus valves are operated by fluid actuated cylinders and having fluid conduits for said cylinders, a plurality of control valves located in the fluid conduits, and operative means whereby the control valve in the conduit leading to the oil valve-oper-

ating cylinder will be opened by the opening of the generator steam valve.

20. In a water gas apparatus wherein the apparatus valves are operated by fluid actuated cylinders and having fluid conduits for said cylinders, a plurality of control valves located in the fluid conduits, a steam whistle alarm, and operative means whereby the control valve in the conduit leading to the steam whistle will be actuated by the operation of the generator steam valve.

21. In a water gas apparatus wherein the apparatus valves are operated by fluid actuated cylinders and having fluid conduits for said cylinders, a plurality of control valves located in the fluid conduits, a steam whistle alarm, and operative means whereby the control valve in the conduit leading to the steam whistle will be opened by the opening of the generator steam valve.

22. In a water gas apparatus wherein the apparatus valves are operated by fluid actuated cylinders and having fluid conduits for said cylinders, a plurality of control valves located in the fluid conduits, and operative means whereby the control valve in the conduit leading to the carburetter oil valve-operating cylinder will be actuated by the operation of the stack valve.

30 23. In a water gas apparatus wherein the apparatus valves are operated by fluid actuated cylinders and having fluid conduits for said cylinders, a plurality of control valves located in the fluid conduits, and
35 operative means whereby the control valves in the conduit leading to the carburetter oil valve-operating cylinder will be closed by the opening of the stack valve.

24. In a water gas apparatus wherein the
40 apparatus valves are operated by fluid ac-
tuated cylinders and having fluid conduits
for said cylinders, a plurality of control
valves located in the fluid conduits, and
operative means whereby the control valve
45 in the conduit leading to the hot valve-oper-
ating cylinder will be actuated by the oper-
ation of the stack valve.

25. In a water gas apparatus wherein the
apparatus valves are operated by fluid ac-
50 tuated cylinders and having fluid conduits
for said cylinders, a plurality of control
valves located in the fluid conduits, and op-
erative means whereby the control valve in
the conduit leading to the hot valve-operat-
55 ing cylinder will be closed by the opening
of the stack valve.

26. In a water gas apparatus wherein the apparatus valves are operated by fluid actuated cylinders and having fluid conduits 60 for said cylinders, a plurality of control valves located in the fluid conduits, and operative means whereby the control valve in the conduit leading to the generator blast valve-operating cylinder will be actuated 65 by the operation of the stack valve.

27. In a water gas apparatus wherein the apparatus valves are operated by fluid actuated cylinders and having fluid conduits for said cylinders, a plurality of control valves located in the fluid conduits, and operative means whereby the control valve in the conduit leading to the generator blast valve-operating cylinder will be opened by the opening of the stack valve. 70

28. In a water gas apparatus wherein the apparatus valves are operated by fluid actuated cylinders and having fluid conduits for said cylinders, a plurality of control valves located in the fluid conduits, a steam whistle alarm, and operative means whereby the control valve in the conduit leading to the steam whistle will be actuated by the operation of the stack valve. 75 80

29. In a water gas apparatus wherein the apparatus valves are operated by fluid actuated cylinders and having fluid conduits for said cylinders, a plurality of control valves located in the fluid conduits, a steam whistle alarm and operative means whereby the control valve in the conduit leading to the steam whistle will be opened by the opening of the stack valve. 85 90

30. In a water gas apparatus wherein the apparatus valves are operated by fluid actuated cylinders and having fluid conduits 95 for said cylinders, a plurality of control valves located in the fluid conduits, and operative means whereby the control valve in the conduit leading to the stack valve-operating cylinder will be actuated by the operation of the carburetter oil valve. 100

31. In a water gas apparatus wherein the apparatus valves are operated by fluid actuated cylinders and having fluid conduits for said cylinders, a plurality of control valves located in the fluid conduits, and operative means whereby the control valve in the conduit leading to the stack valve-operating cylinder will be closed by the opening of the carburetter oil valve. 105
110

32. In a water gas apparatus wherein the apparatus valves are operated by fluid actuated cylinders and having fluid conduits for said cylinders, a plurality of control valves located in the fluid conduits, and operative means whereby the control valve in the conduit leading to the generator blast valve-operating cylinder will be actuated by the swinging of the hot valve into one position and will be reversed by the swinging of the hot valve into its reverse position.

33. In a water gas apparatus wherein the apparatus valves are operated by fluid actuated cylinders and having fluid conduits for said cylinders, a plurality of control valves located in the fluid conduits, and operative means whereby the control valve in the conduit leading to the generator blast valve-operating cylinder will be opened by the swinging of the hot valve into the "up- 130 125

run" position and will be closed by the swinging of the hot valve into the "down-run" position.

34. In a water gas apparatus wherein the apparatus valves are operated by fluid actuated cylinders and having fluid conduits for said cylinders, a plurality of control valves located in the fluid conduits, and operative means whereby the control valve in the conduit leading to the stack valve-operating cylinder will be actuated by the swinging of the hot valve into one position and will be reversed by the swinging of the hot valve into its reverse position.
35. In a water gas apparatus wherein the apparatus valves are operated by fluid actuated cylinders and having fluid conduits for said cylinders, a plurality of control valves located in the fluid conduits, and operative means whereby the control valve in the conduit leading to the stack valve-operating cylinder will be opened by the swinging of

the hot valve into the "up-run" position and will be closed by the swinging of the hot valve into the "down-run" position.

25

36. The combination of an automatically controlled water gas set having operating motors for the apparatus valves of said set and fluid conduits leading to said motors, with a control system comprising interlocking control valves located in said conduits and means operatively associating said control valves with the apparatus valves and said motors whereby the control valves are governed by the action of the apparatus valves.
